(57) **CLAIM**

The ornamental design for a display panel or portion thereof with a graphical user interface as shown and described.

DESCRIPTION

The FIGURE is a front view of a display panel or portion thereof with a graphical user interface showing our new design.

The outermost dot-dash broken lines shown in the drawings represent a display panel or portion thereof with a graphical user interface that form no part of the claimed design. The broken lines in the graphical user interface illustrating portions of the graphical user interface form no part of the claimed design.

1 Claim, 1 Drawing Sheet
